UNITED STATES PATENT OFFICE.

SYLVESTER W. PARKER, OF ALAMEDA, CALIFORNIA.

GRADING MACHINE.

Application filed January 6, 1922. Serial No. 527,427.

To all whom it may concern:

Be it known that I, SYLVESTER W. PARKER, a citizen of the United States, residing at Alameda, in the county of Alameda and 5 State of California, have invented new and useful Improvements in Grading Machines, of which the following is a specification.

This invention relates to improvements in grading machines, and has particular reference to that type of machine adapted to be used for grading various commodities. In 10 the preferred use of the invention it is intended to devise a machine for grading asparagus, although it is obvious that other 15 food commodities, such as olives, walnuts, or vegetables of a like nature as asparagus, may be graded.

The principal object of this invention is to 20 produce a machine which will be capable of operating continuously, and will readily convey a commodity over a grading frame and will then by the disposition of a novel grading construction cause the different sizes of 25 the commodity to pass beneath the grading frame into any conventionally formed receiving means.

A further object of this invention is to 30 provide means cooperating with the grading frame whereby the grading frame will be vibrated and diagonally moved so as to cause 35 the commodity, resting in suitably constructed retainers or buckets, to be placed in a position where the commodity can be readily graded.

35 A further object of this invention is to provide means for supporting the grading frame and the tapered strips of the same, whereby the strips of the grading structure will be positively supported during the 40 process of grading the commodity, without danger of the strips being displaced from the supporting means.

A further object of this invention is to 45 produce a machine of the character described which will be simple in construction, economical to manufacture, and the operation of which will be simple in order that unskilled labor may be employed, and a machine which will be compact in the arrangement of its parts, strong and durable, and capable of handling large quantities of commodities with the greatest of grading accuracy and with a minimum operating cost.

50 Other objects and advantages will be apparent during the course of the following 55 description.

In the accompanying drawings forming a part of this specification, and in which like numerals are employed to designate like parts throughout the same,

60

Fig. 1 is a side elevation of the machine constructed in accordance with my invention,

Fig. 2 is a top plan view of the same,

Fig. 3 is a transverse sectional view on the 65 line 3—3 of Fig. 1, and looking in the direction of the arrows,

Fig. 4 is a fragmentary detail of one of the supporting means for the grading strips,

Fig. 5 is an enlarged fragmentary plan 70 view of the grading apparatus and the mechanism for driving the same, and

Fig. 6 is a perspective view of the buckets or boxes in which are retained the commodity to be graded.

75

In the accompanying drawings wherein for the purpose of illustration is shown a preferred embodiment of my invention, the numeral 10 designates a plurality of uprights adapted to support channel irons 11 and 12, which uprights have likewise connected thereto lower channel irons 13 disposed in parallelism to the ground on which the uprights rest. Supported on the channel irons 11 and 12 and connected thereto is a 85 grading frame designated as a whole by the numeral 14, which frame includes a table portion 15, having extending therefrom and integrally formed therewith enlarged side strips 16 and 17. Interposed between the 90 side strips are a plurality of tapered strips 18 likewise integrally formed with the table portion. It will be manifest by this construction that the tapered strips present graduated outlets 19 through which the commodity to be graded passes and is then received in any conventional receiving means prior to the packing of the commodity.

95 Suitably journaled in bearings provided at the respective front and rear ends of the 100 channel irons, are upper shafts 20 and 21. The shaft 20 has mounted thereon sprockets 22 and 23 while the shaft 21 has mounted thereon sprockets 24 and 25, and on one of its extremities an enlarged sprocket 26, the 105 purpose of which will be hereinafter explained. The channel beams 13 and 13' have likewise journaled in bearings provided adjacent their front and rear extremities, lower shafts 27 and 28, equipped with lower 110 sprockets 29 and 30.

The numerals 31 and 32 designate endless

chains which are trained over the sprockets and have connected thereto spaced buckets or boxes 33 of substantially rectangular configuration, each of the boxes being provided 5 with a plurality of compartments 34 in which are received the asparagus to be graded, which commodity is placed in the compartments in a substantially upright or vertical position. The buckets with the asparagus therein are carried by chains as they pass over the sprockets, the rotary motion being initiated through any suitable source of power attached to a drive pulley 35 mounted on the shaft 20.

15 As shown to advantage in Figures 3 and 4, I have bolted to the underside of the channel irons 11 and 12 supporting means for the tapered strips 18, the said supporting means comprising spaced apertured cross 20 rods 36 having formed thereon and disposed over the threaded aperture thereof, vertically positioned tubes or pipes 37 in which are received stems 38 provided with scarfed heads 39 and in turn detachably fastened to 25 the rods 36 by bolts 40.

Likewise connected to the underside of the enlarged side strips 16 and 17, are the upper extremities of Z brackets 41, which have their lower extremities engaging flexible 30 arms 43 which extend parallel to the channel irons 11 and 12 and together with the eccentrics 44 disposed on a counter shaft 45, impart a reciprocating motion to the grading frame during the operation of the machine. The means for transmitting motion to the shaft 45 includes a spur gear 46, a small endless chain 47 and the large sprocket 26. This mechanism also serves to increase 35 the speed of the counter shaft 45.

40 In order to likewise impart a diagonal movement to the frame, small Z shaped clips are provided. These clips have their upper extremities secured to the underside of the strips 16 and 17 while their lower slotted extremities 48 rest on the base of the channel 45 irons 11 and 12 with pins 49 penetrating the slots formed in the lower extremities of the Z shaped clips. This construction assures a reciprocating and diagonal movement of the 50 grading frame and tends to loosen the asparagus in the box so that the different grades thereof will be in a position to readily pass through the outlets 19, while the supporting means for the strips, as just described, provides for the positive retention of the tapered strips on the supporting means.

The operation of the machine is as follows:-

The machine being started the operator 60 assumes a position adjacent the rear thereof and places a quantity of asparagus, vertically positioned, in the compartments of each of the boxes or conveyors as they pass by. The boxes then travel over the table 65 portion of the grading frame, and as they

travel longitudinally of the tapered strips certain small grades will pass through the various graduated openings, while the larger grades will be retained in the box until they reach graduated openings which will accommodate their size and then the larger sized 70 will pass through the openings. Thus there is provided a grading frame equipped with means whereby various sizes of the asparagus will pass through the openings proportionately to the size of the openings. Any 75 suitable receiving means may be utilized for receiving the graded asparagus after it has passed through the grading frame.

My machine is very simple and economical in construction, and also efficient in use, and it is to be understood that the form of my invention herewith shown and described is to be taken as a preferred example of the same, and that various changes in the shape, 85 size and arrangement of parts may be resorted to without departing from the spirit of the invention or the scope of the subjoined claims.

Having thus described my invention, I 90 claim:-

1. In a grading machine, the combination with a stationary base, of a grading frame positioned on said base and comprising a table portion and a plurality of strips extending from the table portion and tapering towards the rear of the machine, means connected to said frame for transversely actuating the same, and means connected to said frame for distributing the commodity over 100 the surface thereof, said means comprising a plurality of boxes provided with compartments therein, endless chains carried by said base for supporting said boxes and imparting movement thereto, and means for actuating said endless chains.

2. In a grading machine, the combination with a plurality of uprights, of channel irons positioned on said uprights, a grading frame resting in said channel irons, said frame comprising a table portion and a plurality of strips formed integral with the table portion and tapering toward the rear of the machine, means for holding and distributing a commodity over said grading 115 frame, said means comprising a plurality of bottomless boxes having compartments therein of the same area, shafts supported on said channel irons and provided with sprockets thereon, endless chains trained 120 over said sprockets and adapted to support the said boxes, and means for actuating said chains.

3. In a grading machine, the combination with a plurality of uprights, of channel 125 irons positioned on said uprights, a grading frame resting in said channel irons, said frame comprising a table portion and a plurality of strips tapering from the table portion towards the rear of the machine,

means for distributing a commodity over said grading frame, said means comprising a plurality of bottomless boxes having compartments therein of the same area, shafts

5 supported on said channel irons and provided with sprockets thereon, endless chains trained over said sprockets and adapted to

support the said boxes, means for actuating said chains, and means connected to said frame for transmitting a reciprocating and 10 transverse movement thereto.

In testimony whereof I affix my signature.

SYLVESTER W. PARKER.
